UNITED STATES PATENT OFFICE.

EDWARD J. TOMLINSON, OF NEWARK, NEW JERSEY, ASSIGNOR TO SPLITDORF ELECTRICAL COMPANY, OF NEWARK, NEW JERSEY.

ENGINE-STARTING DEVICE.

1,238,958.

Specification of Letters Patent. Patented Sept. 4, 1917.

Application filed November 11, 1913. Serial No. 130,798.

To all whom it may concern:

Be it known that I, EDWARD J. TOMLINSON, a citizen of the United States, residing at Newark, county of Essex, and State of New Jersey, have invented certain new and useful Improvements in Engine-Starting Devices, of which the following is a specification.

My invention in its broader aspects pertains to starters for engines, and in particular it has reference to a starter for gas engines such as the ordinary internal combustion motor used on automobiles. Broadly speaking the present invention consists of an electric motor driven by a suitable source of power, and adapted, through the agency of intermediary members to engage and drive the engine for the purpose of starting the same.

One of the objects is to secure a starter for this purpose that is of simple, and durable construction, yet one in which the driving member is automatic in its action, and to the attainment of this automatic feature I have adopted the use of certain elements, the operation of which lend both simplicity and surety of action to the whole mechanism.

Another object is to provide a starter of this character which is adapted for a simple and ready assembly in working relation with the engine, and from which method of assembly there is to be derived several useful and advantageous features. With these and other objects in view my invention is further characterized by certain features of construction and operation all of which will be readily understood from a study of the following description taken in connection with the accompanying drawing which forms a part of this specification and in which like symbols of reference identify like parts in each of the respective views.

Figure 1 is a longitudinal elevation, partly in section, showing the arrangement of my improved starter and also illustrating one method which I have employed to hold the driving pinion against rotation while the same is being advanced to engage some member operated by the engine.

Fig. 2 is a view similar in nature to Fig. 1 exception, however, being taken to the fact that the driving member is here shown

to be in operative engagement with said engine member. 55

Fig. 3 is a view, on an enlarged scale, illustrating an alternative method which may be used to prevent the driving pinion from rotating while being advanced into said engagement with the engine member. 60

With particular reference to the drawings, 1 is the armature of an electric motor only a portion of which is shown therein. 2 is the frame of said motor which may, if desirable, further serve as a support for the field windings thereof. The motor armature 1 has, at one end, a shaft extension 3. Member 4, having spaced flanges 5 and 6, serves for a plurality of purposes, to be more fully described hereinafter. The flange 5 of said member 4, is adapted to fit on to the end of the casing 2 thereby forming an end plate to inclose and protect the motor armature winding. Member 4 is also provided with a cylindrical recess passing therethrough and so arranged that when end plate 5 is assembled in the position just described said cylindrical recess aligns concentrically with the armature shaft 3. Armature shaft 3 is seen to project somewhat 70 beyond the outer end of flanged member 4. The flange 6, which is shown to be broken off in the drawing, may extend to any suitable distance and may also be adapted, if desirable, to be suitably attached, as by 75 means of bolts, to the bell housing of the engine. This provision furnishes a quick and easy method whereby the starting mechanism may be rigidly mounted in its working relation with the engine. While I have 80 not shown the bell housing and the specific manner in which the flange 6 may be attached thereto, it will be readily apparent to those skilled in the art that any suitable method may be employed. Disposed within 85 the cylindrical recess of member 4 is a hollow cylindrical tube 7 which serves as a bushing, and accordingly may be of any durable and long wearing material such as bronze. Mounted upon armature shaft 3 and adapted to rotate therewith is a hollow 90 sleeve 8. Said sleeve 8 has its internal diameter reduced at one end to form the internal shoulder 9 which furnishes a primary bearing for the armature shaft 3. 95

Some suitable fastening device such as a

key 10 may be used to fasten sleeve 8 rigidly upon armature shaft 3. A pin 11 passes through sleeve 8 and through the shaft 3 to assist the key 10 in holding said sleeve rigidly upon the armature shaft, and further to prevent any creeping action of said sleeve upon said shaft. Externally the sleeve 8 is provided with a smooth cylindrical surface which, when said sleeve is assembled 10 in the above mentioned position, is adapted to rotate within the bronze bushing 7. It will thus be seen that although armature shaft 3 is primarily supported by the internal shoulder 9 of sleeve 8 said armature 15 shaft finds its true bearing in the cylindrical bushing 7 and since said bushing presents a generous bearing surface a proper alignment of the rotating members is always assured, and furthermore the maintenance 20 of sufficient lubrication is greatly facilitated. Internally said hollow sleeve 8 is provided with screw threads 12. A driving pinion 13 with an integrally formed sleeve 14 comprise the driving member of my starter. 25 Said driving member is provided with a circular recess 15 extending longitudinally therethrough and being of a diameter adapted to permit said driving member to be mounted upon motor shaft extension 3 for 30 sliding and longitudinal motion relative thereto. Integral sleeve 14 has its exterior surface provided with threads 16 corresponding to and adapted to mesh with said internal threads 12 of the hollow sleeve 8. 35 Pinion 13 carries the ordinary gear teeth 17 which are adapted to mesh with similar teeth 18 cut in the surface of fly wheel 19. In the drawing only a portion of said fly wheel is illustrated since a more elaborate 40 showing thereof is not necessary to a clear understanding of my invention.

Fastened to flange 6 of member 4 by any suitable means such as bolts 20, is a supplemental member 21 having a depending portion 22, which extends downward to a position in line with the shaft 3. Fastened to the said depending portion 22 is a resilient member 23 extending inward in line with the axis of shaft 3. Said resilient means is seen 45 to be in form of a coil spring which, as shown in Figs. 1 and 2, tapers gradually toward its end and having its last convolution 24 somewhat enlarged for a purpose to be presently described. Driving pinion 13 is 50 provided with a counterbore 25, which shoulder 26, resulting therefrom, is adapted to be engaged by the enlarged convolution 24 of the spring 23 as seen in Fig. 1. Arranged about the shaft 3 within the hollow sleeve 8 55 and preferably at a point adjacent to shoulder 9 thereof, is a second resilient member 27. Said member 27 is designed as a compression spring and to perform the function for which it is intended said spring is 60 designed with considerable stiffness, in order 65 to offer appreciable resistance when being compressed. Said spring is adapted to be engaged by the sleeve 14 of the driving member while pinion 13 is meshing with the engine member 19, to thereby furnish a yielding stop for the inward travel of said driving member. By properly designing spring 27 its force of resistance to compression by sleeve 14 may be made to prevent the further advancement of pinion 13 after said 70 pinion has reached its complete engagement with engine member 19. In other words the force offered by spring 27 when pinion 13 is in complete engagement with engine member 19, as in Fig. 2, is just sufficient to hold 75 said pinion against further advancement due to the resistance offered by the engine when being started. By this construction the compression member 27 serves as a yielding balance for the forces incidental to the starting 80 of the engine, and by such provision the screw threaded members 8 and 14 are relieved of considerable stress that they would otherwise be forced to bear were the driving pinion permitted to unyieldingly contact 85 some rigid member as a limiting stop for its inward travel.

Coming now to a description of the use and operation of my starter, reference is first to be had to Fig. 1 wherein the engine 90 and starting motor are shown to be at rest and the driving pinion 13 in its retracted position. It will be observed that while the driving pinion is assuming this position the counterbore 25 of said driving pinion has 95 moved into the range of spring 23 so that shoulder 26 has encountered the enlarged convolution 24 thereof and has thereby forced said spring into its contracted position shown in Fig. 1. Power may now be 100 applied to the motor armature 1 with the result that said armature with its shaft extension 3 begin to rotate, and since the sleeve 8, as previously mentioned, is secured to shaft 3 said sleeve rotates in unison therewith to 105 serve as a support and journal for said shaft extension 3. Coincident with the rotation of sleeve 8 there is also a tendency of the driving member to rotate, the same being in screw threaded engagement therewith. But 110 spring 23 being in pressing contact with shoulder 26 the frictional resistance resulting therefrom together with the inertia of the driving member is sufficient to overcome 115 this tendency and to restrain said driving member against rotation. Consequently as 120 rotation of the sleeve 8 continues the sleeve 14 is drawn inward by virtue of its threaded engagement with said sleeve 8, while at the same time spring 23 proceeds to expand and 125 follow pinion 13 to thereby maintain the frictional resistance necessary to prevent any rotation thereof. These conditions obtained until pinion 13 has moved inward to such a position as to be in preliminary engage- 130

ment with teeth 18 of engine member 19, at which time the spring 23 has fully expanded and no longer has any holding effect upon the pinion 13. However, said pinion now 5 being in partial mesh with engine wheel 19 is thereby held against rotation and continues to advance into its full mesh position with said engine member. At the time pinion 13 has acquired said full mesh position, seen in Fig. 2, the inner end of sleeve 14 has encountered and compressed the buffer member 27 to a point wherein its force of resistance is sufficient to prohibit the further advancement of pinion 13, 10 whereby said pinion, through the medium of sleeve 8, is rotatively driven by shaft 3 to drive in turn the engine member 19. When the engine picks up on its own power member 19 acquires a speed greater than the 15 speed at which it was driven by pinion 13 while being cranked. The engine thus driving the pinion has the effect of reversing the thrust of the screw threaded sleeve 14. Consequently the driving member is thrown 20 out of mesh with the engine member, the spring 23 serving to prevent rotation of said pinion while it is moving to its normal inoperative position, and further providing a cushion means to receive the impulse of the 25 driving pinion as it is thrown out of said engagement. In this manner my starter performs its complete working cycle.

Considering Fig. 3, there is shown here a 30 modification of the device used to secure the driving pinion from rotation while passing into and out of its driving engagement. In this modified form I have provided a means which may be substituted for the spring 23, and which consists of a bolt 28 having a 35 head 29 and a threaded reduced portion 30. Said bolt is adapted to be suitably fastened to the depending portion 22 of member 21 as by a nut 31. Loosely mounted upon bolt 28 is a flanged washer 32 normally held 40 against head 29 by means of a compression spring 33. Head 29 of this modified form, which as previously mentioned is shown on an enlarged scale in Fig. 3, when assembled 45 in working position is adapted to pass freely within the counterbore 25 of pinion 13, thereby allowing washer 32 to frictionally engage the end of said pinion for the purpose already described.

A feature of my invention is seen to reside 50 in the fact that by the use of resilient means I am able to provide for a gradual application of the driving force between the starting pinion and the engine fly wheel. This provision does away with all shocks and 55 stresses on the working members.

In my present invention I prefer to utilize 60 an electric motor, and I also prefer to have the driving shaft 3 a continuation of the armature shaft as shown, yet I fully appreciate that any suitable type of motor may be

employed, and that the driving shaft may, if desirable, be a counter shaft or the like, suitably connected as by gearing to the driving motor.

Although I have shown but one embodiment of my invention I do not care to be limited to the exact details of construction and operation shown therein, as it is obvious that many changes and alterations may be made by those skilled in the art without 70 deviating from the spirit of said invention, and all of which changes are believed to fall within the scope of the appended claims.

Having thus described my invention what I claim is:—

1. An engine starter having in combination with an engine operated member, a motor driven shaft, a driving pinion having an externally threaded sleeve and mounted upon said shaft for longitudinal movement 80 thereon, an internally threaded sleeve secured to said shaft for rotation therewith and coöperating with said externally threaded sleeve to draw the driving pinion into engagement with the engine member, and 85 yielding frictional means coöperating with an annular shoulder on said pinion to hold the same from rotating while passing into said engagement.

2. An engine starter having in combination with an engine operated member, a motor driven shaft, a driving pinion having an externally threaded sleeve and mounted upon said shaft for longitudinal movement 90 thereon, an internally threaded sleeve fastened to said shaft for rotation therewith and coöperating with said externally threaded sleeve to move said pinion into engagement with the engine member, and resilient 95 means adapted to maintain frictional contact 100 with said pinion for the purpose of holding the same from rotating while passing into said engagement.

3. An engine starter having in combination with an engine operated member, a motor driven shaft, a hollow driving member having an externally threaded sleeve and mounted upon said shaft for longitudinal movement 110 thereon, an internally threaded sleeve fastened to said shaft to rotate therewith and coöperating with the first said sleeve to move said driving member into engagement with the engine member, an internal annular shoulder on said driving 115 member coöperating with resilient means 120 whereby said driving member is frictionally held from rotation while moving into said engagement with the engine member.

4. An engine starter having in combination with a member operated by the engine, 125 a motor driven shaft, a threaded sleeve secured to said shaft for rotation therewith, a driving member mounted upon said shaft and adapted for axial movement relative thereto, said driving member having a 130

- threaded sleeve coöperating with the first said sleeve to move said driving member into engagement with the engine member, a spring adapted to frictionally contact with 5 said driving member to hold the same from rotation while passing into said engagement with the engine member, said first mentioned sleeve serving also as a journal for the motor driven shaft.
- 10 5. An engine starter having in combination with a member driven by the engine, a motor driven shaft, an internally threaded sleeve secured to said shaft for rotation therewith, a hollow driving member having 15 an externally threaded sleeve and mounted upon said shaft for axial movement relative thereto, said sleeves coöperating with each other for the purpose of moving said driving member into and out of driving engagement 20 with the engine member, an annular shoulder formed by a counterbore in said driving member, flexible means frictionally engaging said shoulder whereby said driving member is prevented from rotating while passing 25 into and out of said engagement with the engine member.
6. An engine starter having in combination with a member driven by the engine, a motor, a shaft driven thereby, a driving 30 member, means including said shaft for causing said driving member to pass automatically into and out of driving engagement with the engine member, means co-operating with said driving member to frictionally hold the same from rotation while 35 moving into and out of said engagement with the engine member, said last named means serving also as a buffer member for said driving member when being disengaged 40 from said engine member.
7. An engine starter having in combination with a member driven by the engine, a motor driven shaft, a driving member driven by said shaft to engage and drive 45 said engine member, means to automatically move said driving member into engagement with the engine member and yielding means to absorb the shock of such engagement, a coiled spring having an enlarged convolution at one end thereof, said enlarged convolution being adapted to engage said driving member for the purpose of holding the same from rotation while moving into said engagement with the engine member.
- 55 8. An engine starter having in combination with a member operated by the engine, a motor, a shaft operated thereby, an end plate for said motor having a cylindrical recess therein, a cylindrical bushing within 60 said recess serving as a bearing for said shaft, a sleeve within said bushing and secured to the motor shaft thereby serving as a journal for the same, a driving member mounted upon said shaft and coöperating 65 with said sleeve in such a way that id driving member is automatically moved to drivingly engage said engine member when said motor shaft is operated.
9. An engine starter having in combination with a member operated by the engine, a motor, a shaft operated thereby, an end plate for said motor having a cylindrical recess therein, a cylindrical bushing within 70 said recess serving as a bearing for the motor shaft, a sleeve within said bushing 75 and secured to rotate with said motor shaft thereby serving as a journal therefor, a driving member mounted upon said shaft and coöperating with said sleeve in such a way that said driving member is automatically 80 moved to engage the engine member when the motor shaft is operated, and means carried by said end plate to prevent said driving member from rotating while moving to engage the engine member. 85
10. An engine starter having in combination with a member driven by the engine, a motor, a shaft driven thereby, a driving member mounted upon said shaft and driven thereby, means to move said driving member into and out of engagement with said engine member, an end plate for said motor, a supplemental member attached to said end plate, means attached to said supplemental member and coöperating with said 90 driving member to frictionally hold the same from rotation while moving into said engagement with the engine member, said last mentioned means serving also as an absorption member to receive the impulse of 100 the driving member when thrown out of engagement with the engine member. 95
11. An engine starter having in combination with an engine operated member, a motor driven shaft, a hollow driving member having an externally threaded sleeve and mounted upon said shaft for longitudinal movement thereon, an internally threaded sleeve fastened to said shaft to rotate therewith and coöperating with the 110 first said sleeve to move said driving member into engagement with the engine member, and means coöperating with said hollow driving member to prevent the same from rotating while engaging with the engine member. 115
12. An engine starter having in combination with an engine operated member, a motor driven shaft, a journal for said shaft, a driving member carried by said shaft and means on said journal coacting with means on said driving member to move the same into engagement with the engine operated member, and means to prevent the rotation of the driving member while such engagement is being made. 120
13. An engine starter having in combination with a member operated by the engine, a motor, a shaft operated thereby, an end plate for said motor having a cylindrical 125 recess therein, a cylindrical bushing within 130

recess therein, a hollow sleeve disposed concentrically about the motor shaft and arranged to rotate within said cylindrical recess thereby serving as a journal for said 5 motor driven shaft, internal threads within said hollow sleeve, a driving member mounted upon said shaft and having an externally threaded sleeve adapted to engage the in- ternal threads on said first mentioned sleeve, whereby said driving member is automatically moved longitudinally of said 10 motor shaft to drivingly engage and disengage said engine member.

In witness whereof I affix my signature.

EDWARD J. TOMLINSON.
